(57) **CLAIM**

The ornamental design for a cycling helmet with visor, as shown and described.

DESCRIPTION

FIG. 1 is a top front right isometric view of a cycling helmet with visor showing the design.

FIG. 2 is a bottom rear left isometric view of the cycling helmet with visor of FIG. 1.

FIG. 3 is a front elevation view of the cycling helmet with visor of FIG. 1.

FIG. 4 is a rear elevation view of the cycling helmet with visor of FIG. 1.

FIG. 5 is a left elevation view of the cycling helmet with visor of FIG. 1.

FIG. 6 is a right elevation view of the cycling helmet with visor of FIG. 1.

FIG. 7 is a top plan view of the cycling helmet with visor of FIG. 1; and,

FIG. 8 is a bottom plan view of the cycling helmet with visor of FIG. 1.

The dashed lines in the drawings illustrate portions of the cycling helmet with visor that form no part of the claimed design. The shading lines shown in the drawings represent the approximate three-dimensional contour of the claimed design and are not intended to indicate surface decoration.

1 Claim, 8 Drawing Sheets
